Specification of Letters Patent. Patented Aug. 20, 1918.

Application filed August 15, 1917. Serial No. 186,306.

To all whom it may concern:

Be it known that I, THOMAS J. LOFTUS, a citizen of the United States, residing at Castella, in the county of Shasta and State of California, have invented new and useful improvements in Rotary Engines, of which the following is a specification.

This invention relates to a rotary engine of the internal combustion, multi-cylinder type, such as shown in my co-pending application, Serial No. 196,819, entitled "Rotary engine, and particularly to an engine which is adapted to operate on the two-cycle principle.

One of the objects of the present invention is to provide a rotary cylinder, internal combustion engine operating on the two-cycle principle, in which the crank case and cylinders are mounted eccentrically with relation to the crank shaft and in which both the cylinders and crank shaft revolve. Another object of the invention is to provide a crank shaft of novel construction to which two revolutions are imparted while the cylinders make one revolution, and also to provide a rigid connecting rod for each piston which is adapted to alternately move into and out of engagement with the crank shaft, as will hereinafter be described, to permit a perfect charging and scavenging of the cylinders. Further objects will hereinafter appear.

The invention consists of the parts and the construction and combination of parts as hereinafter more fully described and claimed, having reference to the accompanying drawings, in which—

Figure 1 is a central, longitudinal section through the engine.

Fig. 2 is a cross section of same.

arranged to communicate with the interior of the crank case and an explosive mixture is delivered thereto, as will hereinafter be described.

Surrounding the crank shaft 2 at one end 60 of the crank case 4, and secured by means of a bracket 8 to the bearing A, is a stationary head 9. This head is eccentrically positioned with relation to the crank case and as it is cylindrical in shape, it can readily be seen that the crank case, together with the cylinders, is permitted to revolve about same; packing rings 10 of any suitable description being interposed between the crank case and the head 9 to form a tight joint at 70 this point to prevent leakage of an explosive mixture which is admitted through the head through a pipe 11 which may be connected with a suitable source of supply, as a carburetor or the like not here shown.

Formed integrally with the head or secured thereto, as here shown by means of screws 12 within the crank case, is a plate 13 in which is formed a cam groove which is divided into two connected sections, indicated at 14 and 15. Slidably mounted in each cylinder is a piston 16 and formed as an integral part of each piston is a rigid connecting rod 17, on the lower end of which is formed half journal sections 18. These 85 journals are separated to straddle crank arms 19 secured upon the crank shaft and also to permit a perfect engagement, as will hereinafter be described, with a divided crank pin 20 carried by each crank. One 90 side of each journal member is extended, as at 21, to support a pin or roller 22 which extends into the cam groove formed in the plate 13.

Each piston, with the rigid connecting rod 95

7. A rotary cylinder engine comprising a crank case, a plurality of radially disposed cylinders secured to the crank case, a cylinder shaft journaled to rotate carrying the crank case and cylinders, a crank shaft journaled to rotate independently of the cylinder shaft and eccentrically positioned with relation thereto, a piston in each cylinder, a rigid connecting rod on each piston, a stationary head 10 forming a closure for one end of the crank case, a cam member on said head having a continuous groove formed therein, a pin on each piston rod projecting into said groove, and said groove consisting of one small circular section struck about the center of the cylinder shaft and a large circular connected section which is struck about the crank shaft and conforming with the sweep of the cranks, and a bearing member on each connecting rod adapted to engage the cranks 15 while passing around the large circle of the cam groove.
8. A rotary cylinder engine comprising a crank case, a plurality of radially disposed cylinders secured to the crank case, a cylinder shaft journaled to rotate carrying the crank case and cylinders, a crank shaft journaled to rotate independently of the cylinder shaft and eccentrically positioned with relation thereto, a piston in each cylinder, a rigid connecting rod on each piston, a stationary head forming a closure for one end of the crank case, a cam member on said head having a continuous groove formed 20 therein; a pin on each piston rod projecting into said groove and said groove consisting of one small circular section having a constant radius but being positioned slightly eccentric with relation to the cylinder shaft 25 and a connected larger circular section concentric with the crank shaft and conforming with the sweep of the cranks, and a bearing member on each connecting rod adapted to engage the cranks while passing around the 30 large circle of the cam groove.
9. The combination with the cylinders of a rotary cylinder engine and the pistons in the cylinders, of a rigid connecting rod on each piston, a pin on each rod, a stationary member having a cam groove formed therein 35 into which the pins project and by which the movement of the pistons is controlled so that they remain at their innermost positions during one half of the revolution of the cylinders and are reciprocated once during the other half of the revolution, and means for transmitting said reciprocal movement to revolve a crank shaft.
10. The combination with the cylinders of a rotary cylinder engine and the pistons in the cylinders, of a rigid connecting rod on each piston, a pin on each rod, a stationary member having a cam groove formed therein 40 into which the pins project and by which the movement of the pistons is controlled so

that they remain at their innermost positions during one half of the revolution of the cylinders and are reciprocated once during the other half of the revolution, a crank shaft journaled to rotate and eccentrically 70 positioned with relation to the axis of rotation of the cylinders, said crank shaft having one half the number of cranks that there are cylinders, and a bearing member on each connecting rod adapted to swing into engagement with one of the cranks of the crank shaft during the reciprocal movement of the pistons to rotate the crank shaft.

11. In a rotary cylinder engine, a plurality of radially disposed revolving cylinders, a rotatable crank shaft eccentrically positioned with relation to the axis of rotation of the cylinders, a plurality of radially disposed crank arms secured on the crank shaft, a crank pin secured in the outer end of each crank arm extending outwardly on each side of each crank arm, a reciprocating piston in each cylinder, and a rigid connecting rod on each piston having a divided bearing member formed on the inner end adapted to 80 straddle the outer ends of the crank arms to permit the divided bearings to engage the crank pins during a portion of a revolution of the cylinders and to permit the pistons to transmit two revolutions to the crank shaft 85 during one revolution of the cylinders.

12. In a rotary cylinder engine, a plurality of radially disposed revolving cylinders, a rotatable crank shaft eccentrically positioned with relation to the axis of rotation of the cylinders, a plurality of radially disposed crank arms secured on the crank shaft, a crank pin secured in the outer end of each crank arm extending outwardly on each side of each crank arm, a reciprocating piston in 100 each cylinder, a rigid connecting rod on each piston having a divided bearing member formed on the inner end adapted to straddle the outer ends of the crank arms to permit the divided bearings to engage the crank pins 105 during a portion of a revolution of the cylinders and to permit the pistons to transmit two revolutions to the crank shaft during one revolution of the cylinders, a stationary member having a cam groove formed therein, and a pin on the inner end of each piston connecting rod projecting into engagement with said cam, said cam adapted to transmit one reciprocal movement to each piston during one revolution of the cylinders.

13. In a rotary cylinder engine, a plurality of radially disposed revolving cylinders, a rotating crank shaft eccentrically positioned with relation to the axis of rotation of the cylinders, a reciprocating piston in each cylinder, means independent of the crank shaft controlling the reciprocal movement of the pistons, and a bearing member on the inner end of each piston adapted to engage 115

the crank shaft during a portion of the revolution of the cylinders to transmit rotary movement to the crank shaft.

14. In a rotary cylinder engine, a plurality of radially disposed revolving cylinders, a rotating crank shaft eccentrically positioned with relation to the axis of rotation of the cylinders, a reciprocating piston in each cylinder, a bearing member on the inner end of each piston, crank pins on the crank shaft, and means regulating the reciprocal piston movement to permit the bearing members on the inner ends of the pistons

to engage the crank pins during a portion of the revolution of the cylinders and to move out of engagement with the crank pins during the remaining revolution of the cylinders.

In testimony whereof I have hereunto set my hand in the presence of two subscribing witnesses.

THOMAS J. LOFTUS.
